[57] CLAIM

The ornamental design for a game board, substantially as shown.

DESCRIPTION

FIG. 1 is a top plan view of a game board showing my new design;

FIG. 2 is a bottom plan view thereof;

FIG. 3 is a front elevational view;

FIG. 4 is a back elevational view;

FIG. 5 is a side elevational view as seen from the right of FIG. 1;

FIG. 6 is a side elevational view as seen from the left of FIG. 1;

FIG. 7 is an enlarged sectional view as seen from the plane 7—7 in FIG. 1; and

FIG. 8 is an enlarged sectional view as seen from the plane 8—8 in FIG. 5.
